UNITED STATES PATENT OFFICE

CHARLES A. MOSGROVE, OF WATERBURY, CONNECTICUT, ASSIGNOR TO THE AUTOYRE COMPANY, OF OAKVILLE, CONNECTICUT, A CORPORATION OF CONNECTICUT

OVERALL LOOP

Application filed May 12, 1930. Serial No. 451,624.

This invention relates to new and useful improvements in loop fasteners or securing means such, for example, as are used for connecting the shoulder straps of a pair of overalls to buttons on the upper corner portions of the overall bib, or similar uses.

An object of the invention is to provide a device of this class so constructed that it will not tangle when on the overall strap or when in bulk before being attached to the strap.

A further object is to provide a device of this class including side wires or portions movable relatively to facilitate the attaching or detaching of the device to a button when attaching or detaching the shoulder straps of an overall to the bib portion thereof, or in similar uses.

Other objects and advantages will become apparent from a consideration of the following detailed description taken in connection with the accompanying drawing showing one embodiment of the invention. However, it is to be understood that the invention is not limited to the details shown and that reference should be had to the claims for a definition of the limitations of the invention. Also, while the invention will be described with relation to its use for attaching the shoulder straps of a pair of overalls to the bib portion thereof, it is to be understood that the invention has other applications.

In the drawing:

Fig. 1 is a front elevational view showing portions of an overall bib and strap with the loop of the invention connecting them.

Fig. 2 is a similar view showing the parts as they appear when the device is partially applied.

Fig. 3 is an edge view of the improved loop detached; and

Fig. 4 is an enlarged detail view of the lower end of the buckle on the line 4-4 of Fig. 2.

Referring in detail to the drawing, at 5 is shown a portion of the shoulder strap of an overall to which the invention is attached to be passed over a button 6 having a shank 7 for securing the strap to the overall bib, a portion of which is shown at 8.

As here disclosed my improved loop fas-

tener here designated generally as 9 is formed from a single length of metal, preferably a round wire. Loop 9 includes a top or attaching bar or portion 10 about which the end portion of the strap 5 may be disposed to secure the loop to the strap.

It is obvious from an inspection of the drawing that the length of wire forming loop 9 is bent at spaced points intermediate its ends as at 11 and 12 whereby to form the attaching bar 10. Bends 11 and 12 are preferably in the form of short arcs, the side arms or bars of the loop being then carried toward each other and bent upon themselves as at 13 forming with the attaching bar 10 a partially closed loop for the reception of the shoulder strap 5.

From the bends or turns 13 the arms curve outwardly as at 14 and then inwardly toward each other to provide the relatively large eye 15 and the restricted or narrow neck 16 at the lower end of said eye. At the neck 16 the side arms are again bent outwardly at an incline to form the sides 17 of a small eye 18 the lower end of which is closed by bending the arms at sharp angles as at 19 and 20, disposing the end portions 21 and 22 of the arms in over-lapping relationship.

As shown the bend 19 of the end portion 21 is such as to dispose said end portion in a plane above the end portion 22. The extreme end of the portion 21 is curved downwardly and around the portion 22 forming an eyelet 23 in which said end portion 22 is slidably received. To prevent portions 21 and 22 from ever moving out of over-lapping relationship the extreme end of portion 22 is upset or headed as at 24, head 24 being of sufficient diameter to prevent the portion 22 from being pulled through the eyelet 23.

In use, as before suggested, the loop 9 is secured to the strap 5 as by passing the end of the strap about the attaching bar 10 looping the strap, and then sewing or otherwise securing the end of the strap to the body portion thereof.

When it is desired to secure the strap to the button 6, loop 9 is passed over the head of the button, the size of the eye 15 permitting

this. Next the strap is pulled upwardly to dispose the shank 7 of the button in the eye 18 with the flange of the button disposed over the portions 17, 21 and 22 of the loop 9 as shown in Fig. 1.

Fig. 2 shows the action of the improved loop when being applied to a button or when being removed therefrom. From this figure it will be seen that the side arms of the loop 10 spring or spread apart as the shank 7 of the button moves through the narrow neck 16. The device may be attached by a sudden jerk or otherwise since the end portions 21 and 22 being secured in over-lapping relation- 15 ship by the eye 23 and head 24 cannot move apart to permit the button to pass on through.

Further, it is to be noted that the side bars from each of the eyes incline toward the re- 20 stricted neck 16 whereby to guide the button shank to this neck either in attaching the device to a button or removing it there- from. It will be understood that when re- 25 moving the device from a button, loop 9 will be pressed downwardly forcing the side bars apart as they come in contact with the shank of the button and moving the button into the large eye 15 which will readily pass over the head of the button.

Having thus set forth the nature of my 30 invention, what I claim is:

1. A loop of the class described comprising an attaching bar, a pair of arms extending from said attaching bar and bent inwardly thereunder to form therewith a partially closed loop, said arms then extending outwardly and then downwardly from said loop and then inwardly to provide a relatively large eye, said arms then extending downwardly in opposite directions for a distance and one of said arms then bent inwardly and the other of said arms bent upwardly and in-

wardly to dispose their ends one above the other in over-lapping relationship to form a relatively small eye connected with the relatively large eye by a restricted passage, and one of said arms having its end bent 70 about the other arm and said other arm having its end upset to form a head whereby while the over-lapping end portions of the arms may be moved relatively they cannot be separated.

2. In a loop of the class described includ- 75 ing an attaching portion, a pair of arms ex- tending therefrom, said arms bent to provide a relatively large and a relatively small eye connected by a restricted neck portion, one 80 of said arms at its end portion bent inwardly and the other of said arms at its end portion bent upwardly and inwardly to dispose said end portions in overlapping and rela- 85 tively movable relationship one above the other and in the plane of the arms whereby to close one side of the relatively small eye.

3. A button loop comprising a piece of wire of which a middle portion is bent to 90 provide a suspension loop, and the remain- 95 ing wire portions being formed to include a pair of spring arms providing axially as- sociated button-receiving and button-retaining loops having an intermediate contracted portion, the wire extremities extending in 100 opposite directions and overlapped in the plane of said loops to complete the button- retaining loop, one of said overlapped ex- tremities being free and its end provided with an enlargement, and the other of said overlapped extremities lying within the button-retaining loop and its end bent and provided with a loop loosely surrounding the free extremity.

In testimony whereof I affix my signature.

CHARLES A. MOSGROVE.
